CLAIM

The ornamental design for a light for a vehicle, as shown and described.

DESCRIPTION

FIG. 1 is a front view of the light of our new design in one environment in which it may be used, wherein a first embodiment of the light is to the right and a second embodiment of the light is to the left;

FIG. 2 is a perspective view of the first embodiment of the light of FIG. 1, and the perspective view of the second embodiment is a minor image of FIG. 2;

FIG. 3 is a front view of the first embodiment of the light of FIG. 1, and the front view of the second embodiment is a minor image of FIG. 3;

FIG. 4 is a rear view of the first embodiment of the light of FIG. 1, and the rear view of the second embodiment is a minor image of FIG. 4;

FIG. 5 is a left side view of the first embodiment of the light of FIG. 1, and the right side view of the second embodiment is a mirror image of FIG. 5;

FIG. 6 is a right side view of the first embodiment of the light of FIG. 1, and the left side view of the second embodiment is a minor image of FIG. 6;

FIG. 7 is a top view of the first embodiment of the light of FIG. 1, and the top view of the second embodiment is a minor image of FIG. 7; and,

FIG. 8 is a bottom view of the first embodiment of the light of FIG. 1, and the bottom view of the second embodiment is a mirror image of FIG. 8.

The broken-line drawings in all views of the light are for environmental purposes only and form no part of the claimed design.
